UNITED STATES PATENT OFFICE.

JOHN LAZOWSKI, OF NEWARK, NEW JERSEY.

SHIP-PROTECTOR.

1,280,771.

Specification of Letters Patent.

Patented Oct. 8, 1918.

Application filed January 29, 1918. Serial No. 214,267.

To all whom it may concern:

Be it known that I, JOHN LAZOWSKI, a citizen of Poland, resident of Newark, county of Essex, and State of New Jersey, have 5 invented certain new and useful Improvements in Ship-Protectors, of which the following is a specification.

This invention relates to improvements in torpedo fenders or baffle plates and particularly to types adapted to be secured to the 10 sides of a seagoing vessel.

The principal object of the invention is to provide a fender adapted to sheer off an approaching projectile, diverting the same 15 either above or below the vulnerable part of the ship, thereby protecting the same against danger.

A further object is to provide a device which may be readily applied and which 20 presents a cushion like surface to receive the impact of a projectile and which will automatically reset itself for further or continued operation.

These and other like objects are attained 25 by the novel construction and combination of parts hereinafter described and shown in the accompanying drawings, forming a material part of this disclosure, and in which:—

30 Figure 1 is a side elevational view of a conventional type of ship, indicating the application of the invention.

Fig. 2 is an enlarged fragmental sectional view showing the preferred form of the 35 invention.

Fig. 3 is a perspective view, showing a portion of the exterior hull of the vessel to which the invention is applied.

Fig. 4 is a fragmental vertical transverse 40 sectional view showing the application of the same.

Fig. 5 is a fragmental side elevational view looking from the interior of the vessel.

Fig. 6 is a further enlarged sectional view 45 showing the plunger as passing through the hull of the ship.

Throughout the several views the ship 10, is indicated to be of a conventional type of construction, and has attached to the outer 50 surface of the hull, at a point somewhat above the waterline a plurality of brackets 14, the same extending at spaced intervals entirely around the hull, as do similarly formed brackets 15, below and in register 55 with the upper brackets.

Hingedly secured in both the upper and

lower rows of brackets are leaf plates 16 and 17, respectively upper and lower, the upper plates resting upon the inturned curved edges 19, of the lower plate. Both 60 series of plates may be either left plain, as shown in Fig. 3, but are preferably with a plurality of seats adapted to contain spherical elements or balls 20, forming contact elements adapted to divert the impact 65 of projectiles or the like which may strike thereupon, the balls rotating in their seats which, in addition to the angularity of the disposed plates, causes the projectile to sheer away and fail to make contact with the hull 70 of the vessel.

Secured upon the inner sides of both upper and lower plates are brackets respectively 26 and 27, in which are pivotally engaged rods 28 and 29, the same passing 75 through the hull of the vessel, the openings being provided with stuffing boxes 30, having a flanged exterior and held in position by means of bolts 31, which pass through the flanged elements 32, of the stuffing boxes 80 in which are elongated elliptical holes 33, and pliable packing or stuffing material 35, thereby permitting the rods to move at a slight angle without admitting water to the 85 interior of the ship.

Arranged, interiorly of the hull are rectangular casings 37, supported by braces 38, and securely clamped to the interior of the hull, the inner element 39, having slotted openings 40, for the inner ends of the plunger rods 28 and 29 which are pressed normally outward by means of coiled springs 42, the same abutting against the interior element 39 of the casing at one end and against the fixed collars 44 at the other, the 95 latter being secured to the plunger rods inside of the vessel, so that the same are pressed normally outward, thereby holding the plates extended at an angle. It will be seen that each brace 38 consists 100 of a long flat portion having an angular foot secured to said ship side, and that it terminates in an angular portion one side of which engages the end of the casing and the other side of which engages the side of the 105 casing so as to provide reinforcing means for rigidly holding the casing against headlong displacement should the fenders be struck by a torpedo. These portions are not designated as an inspection of Fig. 2 will 110 readily disclose the same.

From the foregoing it will be obvious

that should a projectile or the like impinge upon the outer surfaces of the plates the projectile will be caused to rise or lower, due to the angularity of the plate, and that 5 the plate will be moved inward, due to the blow.

Having thus described my invention what I claim as new and desire to secure by Letters Patent, is:—

10 1. In a device as described, in combination, a ship side, a rectangular casing secured to said ship side, upon its inner face, a series of brace members each consisting of a long flat portion having an angular foot secured 15 to said ship side, and terminating in an angle portion one side of which engages the side of said casing, and the other side of which engages the end of the casing, a pair of fender plates, springs in said casing, and 20 rods secured to said fender plates and passing through the ship side and carrying shoulders adapted to compressibly engage said springs.

2. In a device as described, in combination, 25 a ship side, formed with an opening,

a fender plate pivoted at its lower end to said ship side, a stuffing box consisting of two opposed caps, one of which has an annular bore and an outwardly-flaring wall, the other of which has a conical portion 30 fitting the flaring wall, each cap having a flange and formed with an opening therethrough, one of said openings having an inclined lateral extension, a casing secured to the inner face of said ship side, the back wall 35 of said casing being formed with an elongated opening, a rod pivoted to the inner side of said fender plate and passing through the openings in said caps, and into the elongated opening of said casing, a flange 40 formed upon said rod working in said casing, a coiled spring wound upon said rod and engaging the back wall of said casing, and a packing snugly fitting in the annular bore of the cap and engaged by the conical 45 portion of the other cap.

In testimony whereof I have affixed my signature.

JOHN LAZOWSKI.
